ABSTRACT OF THE DISCLOSURE

In a die cutting machine having a stationary cutting bed and movable striking arm, a pad of solid resilient resinous material detachably connected to the striking arm and having a smooth continuous surface for direct impact with the back of a conventional die placed on stock spread on the cutting bed for cutting.

This invention relates to machines for die cutting sheet material of all kinds, namely, leather, paper, fabric, vinyl, and/or any combinations and/or derivatives thereof. Such machines have a stationary cutting bed upon which the stock to be cut is spread and a movable striking element or arm by which a sharp edged die is driven by impact through the stock.

Many attempts have been made to improve the construction and performance of such machines by employing cutting beds of all sorts and descriptions. In U.S. Letters Patent No. 2,611,757, Sept. 23, 1952, will be found a discussion of cutting beds composed of maple blocks, nylon, cellulose acetate, resinous vinyl compounds, etc.

The present invention is directed to the improvement of the striking element, not to the cutting bed.

I have discovered that unexpected and important improvements are achieved by providing the striking arm of a clicking press, or other impact die-cutting machine, with a detachable or interchangeable pad of a solid resilient, slightly compressible material having a smooth continuous surface for impact upon the back of a conventional cutting die.

It has been found that die cutting machines so equipped lower the whole factory cost of the die cutting process. Employment of the pad results in less breakage of the dies. They stay sharp for a longer period of use, operate with less noise and with less wear of the cutting bed.

The cutting efficiency of dies operated in such a machine is noticeably improved and while I do not attempt to explain the theory of this improvement it may be that the material of the pad is instantaneously compressed under the impact of the arm on the wide back of the die so as to rotary completion of the full cutting movement or stroke of the die.

Various constructions may be employed for detachably securing the striking pad of my invention to the movable striking arm of the machine. For example, dovetail guideways may be formed on or in the arm to receive correspondingly shaped keys on the pad, or permanent magnets may be embedded in the pad for magnetic connection with an iron striking arm. Or the pad may be provided with a pressure-sensitive adhesive presented on a surface area thereof or as a cover of sheet material.

These and other features of the invention will be best understood and appreciated from the following description of preferred embodiments thereof, selected for purposes of illustration and shown in the accompanying drawings in which:

FIG. 1 is a view in elevation of portions of a conventional clicking press equipped with a striking pad of my invention,

2

FIG. 2 is a view in elevation of a striking arm having a magnetically attached striking pad,

FIG. 3 is a fragmentary sectional view on a larger scale,

5 FIG. 4 is a fragmentary view of a modified construction, and

FIG. 5 is a diagrammatic view showing the cutting action of one type of die.

While my novel cutting pad has a broad application 10 to all die-cutting machines it is disclosed herein in association with a well known type of clicking press, shown for example in U.S. Letters Patent No. 1,629,870, Horgan, to which reference may be had for further details of construction and customary manner of operation.

15 In FIG. 1 it may be assumed that the stationary bed 10 is supported at convenient height by the frame 11 and that the striking arm 12 is mounted to swing transversely above the bed and to move vertically into striking position above a die located anywhere upon sheet stock spread upon the bed. The arm 12 may be of cast iron 20 or of aluminum alloy as disclosed in Letters Patent No. 1,629,870 and its striking face is substantially rectangular in contour.

The striking pad 13 corresponds in contour with the 25 face of the arm 12 and is herein shown as detachably connected thereto by transverse undercut ways 14 secured to the face of the arm and corresponding channels formed in the pad. A latch 15 pivoted to the arm prevents lateral disengagement of the pad.

30 The pad 13 may be fashioned as a slab or mat of any resinous thermosetting product such as a butadiene-acrylonitrile copolymer having a stiff resilient texture and Shore-D hardness of 65-85. The material of the pad may be rendered electro conductive by admixture with 35 carbon black thereto, and as such is useful in a die-cutting machine operating with electric control of the cutting stroke.

In FIGS. 2 and 3 the pad 23 is shown as detachably secured to the cast iron arm 22 of a clicking press by 40 permanent magnets 24 which are incorporated in the pad in flush relation to its inner face.

In FIG. 2 the pad 23 is shown as provided with a facing ply 25 of paper, cloth or cellulose and this may be secured in place by a coating of pressure sensitive 45 cement.

In FIG. 4 the pad 33 is shown as detachably secured to the arm 32 of the press by screws 34 deeply countersunk so as to leave clear the full striking area of the pad.

50 I do not attempt to explain a theory that would account for the very real advantages that have been realized by the employment of my novel striking pad. In the case of wide back dies like that shown in FIG. 5 there may be an instantaneous compression of the pad at the moment of impact which would delay completion of the full cutting stroke. This would somewhat cushion the impact and smooth the progress of the cutting edge of the die through the stock.

60 In FIG. 5, position A, the die is shown as resting on the stock preparatory to cutting. In position B the die is represented as having cut about one-third through the stock and as hesitating on account of the impact compression of the pad, and in position C upon recovery of compression the die has been driven down to complete its cutting stroke.

Another advantage of employing a striking pad of 65 relatively malleable or soft material is that it obviates the danger of scratching the finished surface of the stock as it is drawn into cutting position on the cutting bed of the machine. It sometimes happens that resilient stock drawn from a roll will bulge upwardly into con-

tact with the striking arm and become damaged by a spur or ridge on an unguarded arm of metal.

The striking pad of my invention may be employed with advantage in association with single-edged dies as shown in FIG. 5 or with conventional double edged dies for cutting out right and left blanks.

Having thus disclosed my invention with illustrative embodiments of the same, I claim as new and desire to secure by Letters Patent:

1. In a die cutting machine having a stationary cutting bed and a relatively movable striking arm for use with conventional cutting dies, the invention which consists in a striking pad of solid resilient thermosetting resinous reaction product detachably connected to the striking arm of the machine and having a smooth continuous surface for direct impact with the back of a conventional die placed between it and the cutting bed.

2. A detachable striking pad as defined in claim 1 in which the said pad is detachably connected to the striking arm through the medium of undercut guideways and interfitting keys.

3. A detachable striking pad as defined in claim 1, further characterized in that the detachable pad contains permanent magnets disposed in flush relation in its arm-engaging surface.

4. A detachable striking pad as defined in claim 1,

further characterized in that the material of the pad is of such resiliency and consistency as to retard by momentary compression completion of the full cutting action of a wide back die engaged by the striking pad of the machine.

5. A detachable striking pad as defined in claim 1, further characterized in that the resinous material of the pad is rendered electro-conductive by the admixture of carbon black.

10 6. A detachable striking pad as defined in claim 1, further characterized in that its striking face is covered by an adhesively attached continuous sheet of paper for direct contact with the back of a cutting die.
